UNITED STATES PATENT OFFICE.

SARAH E. RICE, OF SCRANTON, PENNSYLVANIA, ADMINISTRATRIX OF
JAMES N. RICE, DECEASED.

STEAM-GENERATOR.

SPECIFICATION forming part of Letters Patent No. 772,059, dated October 11, 1904.

Application filed August 27, 1903. Serial No. 171,027. (No model.)

To all whom it may concern:

Be it known that JAMES N. RICE, deceased, late a citizen of Scranton, Pennsylvania, invented a new and useful Steam-Generator, of 5 which the following is a specification.

This invention relates to steam-generators, and more particularly to that type characterized by a boiler-coil arranged in close proximity to the point of initial combustion and in communication with a feed-boiler heater in the form of a heating-coil arranged to be heated by the products of combustion after the latter have served first to heat the boiler-coil.

The primary object of the invention is to 15 provide for the introduction of water at the hottest point of the heating-coil and to lead the water from the opposite end of said coil to the hottest point of the boiler-coil, to the attainment of a maximum economy in the consumption of fuel.

Another object of the invention is to provide means whereby the water is pumped into the heating-coil from a tank into which the overflow from the coil is directed when the 25 supply is greater than the demand, steam from the boiler being utilized as the motive agent for the pump.

Other objects subordinate to those enumerated will appear during the following description of the illustrated embodiment of the invention.

In the accompanying drawing is shown a complete steam-generating system including the present invention, a portion of the said 35 system having been claimed in the concurrent application of James N. Rice, Serial No. 120,549.

Within a casing 1, preferably of cylindrical form and closed at its upper end by a wall 1^a, 40 is located a sectional boiler-coil 2, having a drop terminal 3 at its lower end in communication with the upper end of a heating-coil 4, supported within the casing above the boiler-coil. The communication between the two 45 coils is established by pipes 5 and 6, between which is interposed a regulator 7 in communication with a steam-pipe 8, leading from the upper end of the boiler, which regulator constitutes no part of the present invention, but

has been fully described and claimed in the 50 concurrent application above identified. It may be stated, however, that this regulator is operated by steam-pressure to automatically control the flow of water or low-pressure steam from the upper end of the heating-coil 4 to 55 the lower end of the boiler-coil 2. In addition to this provision for the automatic feed of water to the boiler the pipe 6 is provided with a manually-operated valve 9, by means of which the communication between the coils 60 may be entirely severed or the maximum feed determined. The water is supplied to the lower end of the heating-coil 4 from a water-tank 10, communicating through a pipe 11 with a suitable steam-pump 12, preferably of 65 the Worthington duplex type, which is in turn in communication with the heating-coil through the medium of a pipe 13, leading to the lower end thereof. The pump 12 is supplied with steam from the boiler through a 70 valve-controlled pipe 14, tapped into the steam-pipe 8. To facilitate the starting of the apparatus, water is initially pumped into the heating-coil 4 by means of a hand-pump 15, the cylinder of which is in communication 75 with the pipe 13 and with the branch pipe 16, led from the pipe 11 or from the tank 10 direct as desired. The overflow from the heating-coil 4 is permitted to pass back to the tank 10, through an overflow-pipe 17, communicating 80 with the upper end of the coil 4 and provided with a safety-valve 18, which opens under predetermined pressure and permits the water to flow back to the coil.

Within the casing 1, immediately below the 85 boiler-coil, is located suitable heating apparatus, preferably in the form of an oil-burner 19, of any desired construction, supplied with oil from any suitable source—as, for instance, an oil-tank 20—through the medium of pipes 90 21 and 22, between which the regulator 7 is interposed, this regulator serving, as described in the aforesaid concurrent application, to effect the automatic regulation of both the water-feed to the boiler and the fuel-feed to 95 the burner. The oil is preferably vaporized within the vaporizer 23, formed by an enlargement of the pipe 22, located directly over

the burner. This particular form of heating apparatus is not an essential element of the invention, but has been described to facilitate the disclosure.

5 The heating apparatus is started in the usual manner by a pilot-light, provision for which is made by leading a valve-controlled branch pipe 24 from the pipe 21 to the interior of the casing 1, immediately adjacent to the vaporizer 23 therein.

Briefly the operation of the generating apparatus is as follows: The valve 18 in the overflow-pipe 17 is set to open at any desired pressure, preferably somewhat higher than that which will effect the automatic stopping of the pump 12. The pilot-burner is then lighted to heat the vaporizer, after which the vapor issuing from the burner 19 may be ignited. The hand-pump 15 is then put in operation to supply water to the feed-water heating-coil 4, through which it will circulate in an upward direction, passing thence through the pipes 5 and 6 to the lower end of the boiler-coil, within which steam will be generated. As soon as this generation is sufficient to supply the pump 12 the latter will be put in operation to force the circulation through the feed-water heating-coil 14 and thence to the boiler-coil, the regulator 7 serving to regulate the supply of water to the boiler and fuel to the burner in accordance with the fluctuating demand upon the apparatus.

It should be particularly noted that the arrangement of the coil 4 in superposed relation to the coil 2, located directly above the burner 19, facilitates the heating of both coils by a single burner, and that by arranging the circulation in the manner described the water is introduced to the heating-coil 4 at the hottest point thereof, and after then circulating through the entire length of the coil is introduced to the boiler-coil at the hottest point thereof and, in fact, in immediate proximity to the point of initial combustion. This arrangement obviously results in a maximum generation of steam and a minimum consumption of fuel.

It is thought that from the foregoing the construction and operation of the herein-described invention will be clearly apparent; but it is to be distinctly understood that the invention is not limited to the construction and arrangement of parts described, as, on the contrary, the right is reserved to effect such changes, modifications, and variations of the illustrated structure as may be fairly embraced within the scope of the protection prayed.

What is claimed is—

60 1. In an apparatus of the class described, the

combination with a casing entirely closed at its upper end; of a heater within the casing, a boiler-coil above the heater and a feed-water coil above the boiler-coil, said coils being coaxial and entirely exposed to the products of combustion rising from the heater, means for supplying water to the lower end of the heating-coil, and a pipe located exterior to the casing and directly connecting the upper end of the heating-coil with the lower end of the boiler-coil.

2. In an apparatus of the character described, the combination with a heater; of a boiler-coil and a feed-water heating-coil both arranged to be heated thereby, a water-tank, pipes establishing connection between the water-tank and the opposite ends of the heating-coil, and a pipe for establishing direct communication between one end of the heating-coil and the lower end of the boiler-coil.

3. In an apparatus of the character described, the combination with a casing closed at its upper end; of a heater, a boiler-coil and a feed-water heating-coil in superposed relation within the casing and above the heater, a water-tank, means for leading water from said tank to the lower end of the heating-coil, said means including a pump, means for leading water or low-pressure steam from the upper end of the heating-coil to the lower end of the boiler-coil, and means for leading steam from the upper end of the boiler-coil to the pump to operate the same.

4. In an apparatus of the character described, the combination with a casing closed at its upper end; of a boiler-coil and a superposed feed-water heating-coil located within the casing above the boiler-coil, a heater located below the boiler-coil, a water-tank, means for leading water from said tank to the lower end of the heating-coil, said means including a steam-pump, means for leading hot water or low-pressure steam from the upper end of the heating-coil to the lower end of the boiler-coil, means for leading steam from the upper end of the boiler-coil to the pump to operate the same, an overflow-pipe establishing communication between the water-tank and the upper end of the heating-coil, and a pressure-operated valve in the overflow-pipe.

In testimony that I claim the foregoing as the invention of JAMES N. RICE, deceased, I have hereto affixed my signature in the presence of two witnesses.

SARAH E. RICE,
*Administratrix of the estate of James N.
Rice, deceased.*
